UNITED STATES PATENT OFFICE.

WILLIAM J. GOING, OF AMSTERDAM, NEW YORK, ASSIGNOR TO KLAUDER-WELDON
DYEING MACHINE COMPANY, OF AMSTERDAM, NEW YORK, A CORPORATION OF
NEW YORK.

YARN-TREATING MACHINE.

1,258,764.

Specification of Letters Patent. Patented Mar. 12, 1918.

Application filed March 9, 1916. Serial No. 83,007.

To all whom it may concern:

Be it known that I, WILLIAM J. GOING, a citizen of the United States, residing at Amsterdam, in the county of Montgomery and State of New York, have invented certain new and useful Improvements in Yarn-Treating Machines, of which the following is a full, clear, and exact description, such as will enable others skilled in the art to 10 which it appertains to make and use the same.

This invention relates to yarn treating apparatus, and particularly to apparatus for washing, scouring and dyeing yarn.

15 One of the objects of the invention is to provide a practical and efficient machine of the character referred to. Another object of the invention is to provide a simple construction of machine wherewith long delays, 20 due to possible abnormal operation, as by misplacement of the yarn, are avoided. Another object of the invention is the provision of a practical machine wherewith breakage of the machine and of the yarn and soiling 25 of the latter are largely avoided.

Other objects will be in part obvious and in part pointed out hereinafter.

The invention accordingly consists in the features of construction, combinations of 30 elements and arrangement of parts which will be exemplified in the construction hereinafter set forth, and the scope of the application of which will be indicated in the following claims.

35 In the accompanying drawings forming part of this specification, and wherein similar reference characters refer to similar parts throughout the several views,—

Figure 1 is a front elevation of a machine 40 of the character described for scouring yarn;

Fig. 2 is a rear elevation of the machine shown in Fig. 1 and showing also a portion of another similar machine at the left-hand 45 side;

Fig. 3 is a detail perspective view of the form of shift mechanism employed in Figs. 1 and 2;

Fig. 4 is a front view of a portion of Fig. 50 1, illustrating a modified form of shift mechanism associated therewith;

Fig. 5 is a rear view of the machine shown in Fig. 4;

Fig. 6 is an end view of the shift mechanism of Fig. 4; and

Fig. 7 is a view of a dyeing machine with the form of shift mechanism illustrated in Fig. 4.

In Figs. 1 to 3 the invention is herein disclosed as embodied in a machine similar to 60 that forming the subject-matter of applicant's companion application filed March 11, 1915, No. 13,596 (1915), though it is to be noted that the invention is capable of being differently embodied without departing 65 from the spirit thereof. 1 is the frame of the scouring machine, the various shapes of portions of which will be best understood from the drawings, and which may be varied indefinitely in shape according to the 70 detail of the remainder of the apparatus. 2 is an electric motor driving the apparatus through a gear 3. A second gear 4 is mounted on a countershaft 5, as is also a gear 6. The main shaft of the machine is 75 numbered 7 and is driven by a gear 8, meshing with the gear 6 through the collar of a clutch 9. A worm 10 drives the worm wheel 11 on the shaft 12, presently to be referred to, and a gear 13, through another gear 14 80 on the shaft 15 and worm 16 upon that shaft, drives a worm gear 17 turning the shaft 18. On the right-hand end of the shaft 7 (Fig. 1) is loosely journaled a bevel gear 19 driving another bevel gear 20, presently to be further described; a clutch 21, the collar 22 of which is fastened to the shaft, connects the gear 19 thereto or throws it out, as may be desired.

Turning now to Fig. 2 in connection with 90 Fig. 1, it will be seen that the apparatus is located in a tank 23, and in part consists of a conveyer for the material to be treated, this conveyer comprising two aprons, marked 24 and 25. The construction of 95 these aprons may be similar to that set forth in the prior application above referred to, and reference thereto may be had for a fuller description. It is sufficient to here state that the aprons 24 and 25 have a circuitous course in the liquor in the tank 23, and that the yarn is carried by and between these aprons into, through and out of the liquor.

The yarn passes into the machine from the 105 table 26 on one side of the machine and

leaves it on the other side as the apron passes over the sprocket 27 (see Figs. 2 and 3). Upon leaving the apron at the sprocket 27, it passes from the machine and between 5 the squeezing rolls 28 and 29, which are constructed and operate as described in the prior application referred to.

At the left in Fig. 2 is shown the mechanism which is used when a plurality of the 10 machines are coupled together. Extensions 30 of the upper part of the machine frame register with the outside of the tank or vat 31 of a second machine. From the shaft 18 of the lower roller 28, by means of a 15 sprocket, is driven a transfer roller 33 carrying the yarn to the apron 34 of a second machine similar to the first. The yarn being brought up from the first tank on the apron 25 is transmitted to the squeezing 20 rolls, and is then carried to the transfer roll 33, which in turn drops it upon the apron 34 of the succeeding machine.

As these machines are driven by power and the load upon them varies considerably, 25 an ample surplus of power must be provided; and as the squeezing rolls are under very heavy pressure, any operation about the machines is dangerous unless abundant facilities for stopping them quickly be provided. This has been arranged in the apparatus herein illustrated. Referring to Figs. 1, 2 and 3, one form of stopping system is illustrated. The lever, or member, 35 is an ordinary shifting lever working 30 through the link 36, the lever 37, pivoted at 38 and operating the collar of the clutch 9, connecting the gear 8 to the shaft 7. A spring 39 of ample power to throw the lever is connected to the link 36 and as a factor of safety another spring 40 is also provided, so that when the lever 35 is released, 40 it will certainly be operated. The lever 35 is held in place by a rotary dog, as a cam 41 formed upon a gear 42. A notch 45 behind the cam holds the lever 35 in place, but when the gear 42 is revolved by moving the handle 43, the inclined surface of the cam is presented to the lever 35; the springs 39, 40 pull over the lever 35 and shift the 50 clutch 9, bringing the machine to an instantaneous stop, inasmuch as the worm gears 10, 16 serve as effective brakes. At 44 is an abutment, or board, mounted rigidly upon a shaft 45; connected to the shaft at 55 each end is a bell crank lever 46. On one side of the machine is a bar 47, connected at one end to the lever 43 and sliding in a guide 48, a stop 49 limiting its movement. One of the bell crank levers 46 connects 60 with this bar at a slotted end 50. If the hand or the yarn is thrust against the board 44 with sufficient force, the lever 46 will, by the rotation of the shaft 45, be thrown to the right in Fig. 1, throwing with it the 65 bar 47 and thus operating the lever 43, turn-

ing the cam 41 so as to release the lever 35, and throwing out the main clutch 9 of the machine. On the other side of the machine the corresponding bell crank lever 46 is connected to a sliding bar 51, to which are 70 also connected the handles 52, 53, the latter working against a spring 54. At the left-hand end of the bar 51 (see Fig. 2) is a lever 55 and an abutment, or board, 56, is connected to the shaft to which this lever 75 is keyed. This board, as will be observed, is in front of the rollers 28, 29, which squeeze the yarn, and it will be obvious from the connections that if this board be pressed toward the rolls, it will throw the bar 51 to the left and operate the bell crank lever 46 and bar 47, thus, as already explained, 80 throwing out the main clutch of the machine.

The construction hereinbefore described is 85 similar to that of the prior application above mentioned, and is appended with the view of enabling one to herein clearly understand the general construction and operation of the machine, and particularly the construction and operation of the stopping mechanism and its relation to the other functions 90 of the prior machine. It will be observed that, in order to stop the machine by the construction hereinbefore described, the cam 41 has to be turned, and that the turning of this cam is accomplished by a movement of the rod 47, in consequence of which the boards 44 and 56 are likewise turned.

When the machine is running, it may be 100 desired to stop it without disturbing the boards 44 and 56, and to this end the construction illustrated in Figs. 4, 5 and 6 has been devised, in which, nevertheless, the features of stopping by proper movement of 105 the boards or abutments 44 and 56 are maintained. Referring now more particularly to Figs. 4, 5 and 6, the numeral 56 indicates the board or abutment in front of the squeezing rolls and 55 indicates the bell crank 110 lever or depending arm which is moved by said abutment, as hereinbefore described. Applicant has chosen to explain the different form of shift or stop mechanism in connection with the board or abutment for the 115 squeezing rolls, but it will be obvious that its construction and operation are as well applicable to the board adjacent the feed table 26, and in divers other places. The abutment 56 lies in front of the squeeze rolls 28 and 29 with its lower edge spaced from the adjacent apron a sufficient distance to permit the passage of yarn of normal depth to said rolls. The abutment 56 extends the full width of the aprons and should the 120 yarn be bunched or massed so as to increase in thickness at any point in its width it will be forced against the abutment by the movement of the conveyer aprons and will turn the abutment on its axis. The lower 125 130

end of arm 55 is in coöperative relation with a rod 57, disposed longitudinally of the tank 23 and guided in keepers 58 on one side of the tank. When an abnormal operation of 5 the machine occurs, as by reason of the bunching of the yarn hereinbefore referred to, the present invention provides for automatically cutting out the driving relation between the driving and driven elements, 10 and this "cutting out" is referred to herein by the term "disengaging" or the like, as being a simple term to indicate the function accomplished. This term is, of course, intended to include any of the many ways in 15 which a machine is directly connected and disconnected from its power, as by clutches, belt-pulleys, etc.

The numeral 59 indicates a manually operative member, or shift lever, connected by 20 a link 60 with the lever 37 fulcrumed on the side of the tank and connected to the rotatable driving clutch or element 9 which rotates with the shaft 7. By shifting the lever 59 the driving clutch 9 may be engaged 25 and disengaged with the driven gear 8 and thus power applied and cut off from the conveyer aprons. The lever 59 is fulcrumed on the side of the vat in any suitable way, as by being pivoted in the strengthening brackets 30 61 fastened to the vat. The numeral 62 indicates a movable device or member, which, in its specific aspect, is a motor-device and comprises an upstanding arm pivoted on the same axis as is the lever 59 and 35 having a handle 62' and a lower horizontally disposed arm 63 on which is a weight 64 adjustable on arm 63, the weight tending to move the device 62 in the direction indicated by the arrow A. The device 62 is 40 herein termed a "motor-device," inasmuch as it automatically moves in a predetermined manner under the influence of the weight 64 when it is free to move, and energizes other parts. The motor-device is adapted, 45 when moved in a predetermined direction, to move the lever 59 in a direction to cause disengagement of the driving and driven elements hereinbefore referred to, so as to cut off the apparatus from its power, and in the 50 present embodiment is provided with a projection, a square lug 65, which engages the edge of the lever 59 and shifts said lever. When the shift lever 59 is in such position that the driving and driven elements are engaged, the motor-device 62 is held in such 55 position as not to energize the shift lever 59 by means of a stop-dog 66 which is adapted to be moved into and out of engagement with the motor-device. In the present embodiment the dog 66 is rotatable into and 60 out of position in the path of the motor-device and is comprised in a semi-circular gear 67, the flat face 68 of which may be disposed across the path of the motor-device or 65 outside of said path. This dog is rotatably

mounted on the side of the tank, and its teeth mesh with a gear 69 fixed on a shaft 70 extending across the tank, the other side of the shaft being provided with a trip-arm 71 fastened thereto so as to rotate therewith and with the rotatable dog 66. The elements just referred to are so relatively arranged that when the motor-device 62 is drawn back into the position from which it moves to cause disengagement of the driving and driven elements, the dog 66 may stand opposite the edge of the element 62 so as to stop disengaging movement of said element, and at this time the trip-arm 71 will be in a horizontal position. This latter arm is held in such horizontal position by means of a trip 72 carried by an arm or lever 73, one end of which is pivoted to a fixed bracket 74, and the other end of which is slotted for engagement of a pin 75 carried by the rod 57. The rod 57 is strained in a direction to place the trip 72 beneath the trip-arm 71 by means of a spring 76. The trip 72 is pivotally connected to the lever 73 so that it may be rotated upwardly 90 to escape the end of the trip-arm 71 at certain times, its lowermost position being determined by a stop 77 on lever 73. On the shaft 70 is a rotatable sleeve 78, having at one end a trip-arm setter, comprising an 95 arm 79 rotatable with said sleeve and disposed opposite the trip-arm 71, the sleeve 78 being provided with a handle 80 for conveniently rotating the same. The depending arm 55 may pass through a slot in the 100 rod 57 or may abut against a pin 81' on said rod, as illustrated.

The operation of the machine in conjunction with the form of shift or stop illustrated in Figs. 4, 5, and 6 will be apparent 105 from the foregoing description, but may be briefly described as follows: When the yarn becomes so bunched as to move the abutment 56, the arm 55 will move the rod 57 against the resistance of the spring 76 110 and will cause the lever 73 to rotate, thus drawing the trip 72 from beneath the trip-arm 71 so that the latter will be free to rotate. The weight 64 will then cause the motor-device or arm 62 to advance in the direction to cause the lug 65 to engage the shift lever 59, thus effecting rotation of the dog 66 into its position out of the path of the device 62, the trip-arm 71 being lowered on account of the rotation of the shaft 70. 115 The lug 65 will strike against the edge of the trip lever 59 and cause disengagement of the driving and driven elements, thus cutting off the power and bringing the machine to rest before any damage has been 120 done. To reset the apparatus the handle 62' is grasped and the motor-device 62 is drawn back. The sleeve shaft 78 is then rotated by means of the handle 80 in the direction so that the trip setting arm 79 will 125

rise and lift the trip-arm 71 and sweep the same past the end of the trip 72, the latter rising on its pivot to permit its passage. As the trip-arm 71 rises the shaft 70 will 5 rotate, causing the gears on the dog and shaft to set the dog into stop position relative to the device 62. The trip-arm 72 will descend to its position limited by the stop 77, and the trip-arm 71 will rest thereon 10 and hold the dog 66 against the pressure of the device 62. It will be observed that the trip lever 59 may be operated freely so as to cut in and cut out the power irrespective of the movements of the device 62. Preferably when the device is set in position with 15 the driving and driven elements engaged, the trip lever is locked in its position by means of a pawl, or coupling, 81 pivoted thereto and engaging the lug 65, this pawl 20 having a handle 82 alongside the handle of lever 59. The lever 59, at its upper part, is guided in a slotted bracket 83 secured to the tank wall.

Fig. 7 illustrates the invention embodied 25 in a form of dyeing machine having a conveyer comprising a rotatable reel carrying rotatable yarn sticks, each stick having a star wheel adapted to coöperate with a device to effect turning of the sticks in one 30 direction on their axes during operation of the dyeing machine. Turning of the sticks in the opposite direction is restrained by the customary ratchets. The reel is indicated at 100, and the sticks 101 are provided with 35 star wheels 102 and pawls 102'. They are shown inside the tank or casing 103, the star wheels coöoperating at the top of the tank with a stick-turning device comprising a pivoted arm or abutment 104' on the inside 40 of the tank having an arm 104 fixed to the pivot 105 at the outside of the tank. The reel normally rotates in the direction of the arrow B. Should any yarn stick be prevented from rotating on its mounting in the 45 reel, the arm 104 will be pressed and rotated on its axis in the direction indicated by arrow C. 106 is a weighted lever pivoted at 107, one of its arms 108 being in the path of a pawl 109 pivoted on arm 104, this 50 pawl being held to rotate with arm 104 in the direction of arrow C. The other or depending arm of lever 106 is linked to a lever 110 pivoted on the frame at 111, one end of this lever coöperating with the pin 55 81 to move the rod 57 against the resistance of the spring 76 to remove the trip 72 from beneath the trip-arm 71 and permit the dog 66 to rotate out of the way of the motor-device 62. The stop or shifting device illustrated in Fig. 7 is the same as that shown 60 in Figs. 4, 5 and 6, except that all its parts are on the same side of the tank.

For discharging the contents of the tanks when desired, a valve, as illustrated in Fig. 65 1, may be employed. The numeral 120 in-

dicates a valve casing communicating with the tank, the valve being indicated at 121 and its seat at 122 opposite the outlet. A foot lever 123 is fulcrumed on the valve casing, one arm of this lever having a pedal piece 124 and the other arm having a pin and slot connection with the stem 125 of the valve. Pivottally connected to the foot lever 123 is a pawl 126, the notch 127 of which is adapted to engage a stationary 70 member 128 to hold the valve in open position, a spring 129 being connected to the pawl and the member 128, so that its stress tends to urge the pawl notch against the member 128, and also tends to close the 80 valve and hold it closed when the pawl is released for interlocking engagement with the member 128. The pawl 126 has a pedal piece 130, depression of which lifts the notch of the pawl out of locking engagement with member 128, permitting the spring 129 to 85 close the valve.

As many changes could be made in the above construction and many apparently 90 widely different embodiments of this invention could be made without departing from the scope thereof, it is intended that all matter contained in the above description or shown in the accompanying drawings shall 95 be interpreted as illustrative and not in a limiting sense.

It is also to be understood that the language used in the following claims is intended to cover all of the generic and specific features of the invention herein 100 described and all statements of the scope of the invention, which, as a matter of language, might be said to fall therebetween.

Having described my invention, what I claim as new and desire to secure by Letters Patent is—

1. In an apparatus of the character described, in combination, a driving element, a driven element, a conveyer for material to be treated, a movable abutment adjacent the path of the material, and means adapted to cause disengagement of said elements comprising connections operable by said abutment, said connections comprising a member movable to shift one of said elements, and a dog rotatable into and out of position preventing said shifting movement of said member.

2. In an apparatus of the character described, in combination, a driving element, 120 a driven element, a conveyer for material to be treated, a movable abutment adjacent the path of the material, means adapted to cause disengagement of said elements comprising connections operable by said abutment, said connections comprising a motor-device adapted to effect disengagement of said elements on movement in one direction, and a stop movable into and out of the path 125 of movement of said motor device.

3. In an apparatus of the character described, in combination, a driving element, a driven element, a conveyer for material to be treated, a movable abutment adjacent the path of the material, means adapted to cause disengagement of said elements comprising connections operable by said abutment, said connections comprising a motor-device adapted to effect disengagement of said elements on movement in one direction, a stop movable into and out of the path of movement of said motor-device, and manual means adapted to effect disengagement of said elements comprising a shift lever operable independently of the movement of said motor-device.

4. In an apparatus of the character described, in combination, a driving element, a driven element, a conveyer for material to be treated, a movable abutment adjacent the path of the material, means adapted to cause disengagement of said elements comprising connections operable by said abutment, said connections comprising a motor-device adapted to effect disengagement of said elements on movement in one direction, a stop movable into and out of the path of movement of said motor-device, manual means adapted to effect disengagement of said elements comprising a shift lever operable independently of the movement of said motor-device, and means adapted to couple said shift lever to said device.

5. In an apparatus of the character described, in combination, a driving element, a driven element, a conveyer for material to be treated, a movable abutment adjacent the path of the material, means adapted to cause disengagement of said elements comprising connections operable by said abutment, said connections comprising a motor-device adapted to effect disengagement of said elements on movement in one direction, a stop movable into and out of the path of movement of said motor-device, manual means adapted to effect disengagement of said elements comprising a shift lever operable independently of the movement of said motor-device, and means adapted to couple said shift lever to said device, said coupling being arranged to permit shifting movement of said motor-device relative to said lever.

6. In an apparatus of the character described, in combination, a driving element, a driven element, a conveyer for material to be treated, a movable abutment adjacent the path of the material, means adapted to cause disengagement of said elements comprising connections operable by said abutment, said connections comprising a member movable to shift one of said elements, a dog rotatable into and out of position preventing said shifting movement of said member and a manually operable member to rotate said dog.

7. In an apparatus of the character described, in combination, a driving element, a driven element, a conveyer for material to be treated, a movable abutment adjacent the path of the material, means adapted to cause disengagement of said elements comprising connections operable by said abutment, said connections comprising a member movable to shift one of said elements, a gear member having a dog rotatable into and out of position preventing said shifting movement of said member, and a manually operable lever having a gear meshing with said gear member.

8. In an apparatus of the character described, in combination, a driving element, a driven element, a conveyer for material to be treated, a movable abutment adjacent the path of the material, and means adapted to cause disengagement of said elements comprising connections operable by said abutment, said connections comprising a slideable bar operatively connected with said abutment, a lever pivoted on said bar, gear teeth carried by said lever, a gear with which said teeth mesh, a dog rotatable with said gear, and a member movable to shift one of said elements, said dog being movable into and out of the path of said member.

9. In an apparatus of the character described, in combination, a driving element, a driven element, a conveyer for material to be treated, a movable abutment adjacent the path of the material, and means adapted to cause disengagement of said elements comprising connections operable by said abutment, said connections comprising a slideable bar operatively connected with said abutment, a lever pivoted on said bar, gear teeth carried by said lever, a gear with which said teeth mesh, a dog rotatable with said gear, and a motor-device movable to shift one of said elements, said dog being movable into and out of the path of said motor-device.

10. In an apparatus of the character described, in combination, a driving element, a driven element, a conveyer for material to be treated, a movable abutment adjacent the path of the material, and means adapted to cause disengagement of said elements comprising connections operable by said abutment, said connections comprising a motor-device movable to shift one of said elements, a manually operable shift lever adapted to be shifted by said motor-device to disengage said elements, and a stop operable by said abutment to permit shifting movement of said motor-device.

11. In an apparatus of the character described, in combination, a driving element, a driven element, a conveyer for material to be treated, a movable abutment adjacent the path of the material, and means adapted to cause disengagement of said elements com-

- 6
- prising connections operable by said abutment, said connections comprising a motor-device movable to shift one of said elements, a manually operable shift lever adapted to be shifted by said motor-device to disengage said elements, and a stop operable by said abutment to permit shifting movement of said motor-device, said stop being out of the path of movement of said shift lever.
- 10 12. In an apparatus of the character described, in combination, a driving element, a driven element, a conveyer for material to be treated adapted to be operated by said driven element, a movable device, adapted on movement in a predetermined direction, to disengage said elements, and means operable from a point adjacent the path of the material to cause said device to move in said direction comprising a dog movable into and out of engagement with said device, and a trip adapted to hold the dog in engagement therewith.
- 15 13. In an apparatus of the character described, in combination, a driving element, a driven element, a conveyer for material to be treated adapted to be operated by said driven element, a movable device, adapted on movement in a predetermined direction, to disengage said elements, and means operable from a point adjacent the path of the material to cause said device to move in said direction comprising a dog rotatable into and out of engagement with said device, an arm rotatable with said dog, and a trip movable into and out of engagement with said arm.
- 20 14. In an apparatus of the character described, in combination, a driving element, a driven element, a conveyer for material to be treated adapted to be operated by said driven element, a hand operable lever adapted to be operated to cause engagement and disengagement of said elements, a pivoted motor-device adapted to move said hand operable lever to effect disengagement of said elements, and means operable from a point adjacent the path of said material to cause said device to operate.
- 25 15. In an apparatus of the character described, in combination, a driving element, a driven element, a conveyer for material to be treated adapted to be operated by said driven element, a hand operable lever adapted to be operated to cause engagement and disengagement of said elements, a pivoted motor-device having a projection to engage said hand operable lever and move the latter to effect disengagement of said elements, and means operable from a point adjacent the path of the material to cause said device to operate.
- 30 16. In an apparatus of the character described, in combination, a driving element, a driven element, a conveyer for material to be treated adapted to be operated by said driven element, a manually operable lever adapted to be operated to cause engagement and disengagement of said elements, a pivoted motor-device adapted to move the latter to effect disengagement of said elements, and means controlled by said abutment adapted to effect disengagement of said elements comprising a pivoted motor-device adapted to engage said manually operable lever and move it in a direction to effect disengagement of said elements.
- 35 17. In an apparatus of the character described, in combination, a driving element, a driven element, a conveyer for material to be treated adapted to be operated by said driven element, a manually operable member adapted to cause engagement and disengagement of said elements, an abutment, and means controlled by said abutment adapted to effect disengagement of said elements, comprising a pivoted motor-device adapted to engage said manually operable member and move it in a direction to effect disengagement of said elements.
- 40 18. In an apparatus of the character described, in combination, a driving element, a driven element, a conveyer for material to be treated adapted to be operated by said driven element, a manually operable member adapted to cause engagement and disengagement of said elements, an abutment, means controlled by said abutment adapted to effect disengagement of said elements comprising a pivoted motor-device adapted to engage said manually operable member and move it in a direction to effect disengagement of said elements, and a rotatable stop dog movable into and out of the path of said device.
- 45 19. In an apparatus of the character described, in combination, a driving element, a driven element, a conveyer for material to be treated adapted to be operated by said driven element, a manually operable member adapted to cause engagement and disengagement of said elements, an abutment, means controlled by said abutment adapted to effect disengagement of said elements comprising a pivoted motor-device adapted to engage said manually operable member and move it in a direction to effect disengagement of said elements, a rotatable stop dog movable into and out of the path of said device, and a trip arm rotatable with said dog.
- 50 20. In an apparatus of the character described, in combination, a driving element, a driven element, a conveyer for material to be treated adapted to be operated by said driven element, a manually operable member adapted to cause engagement and disengagement of said elements, an abutment, means controlled by said abutment adapted to effect disengagement of said elements comprising a pivoted motor-device adapted to engage said manually operable member and move it in a direction to effect disengagement of said elements.

gagement of said elements, a rotatable stop dog movable into and out of the path of said device, a trip arm rotatable with said dog, and a trip movable into and out of engagement with said trip arm.

21. In an apparatus of the character described, in combination, a driving element, a driven element, a conveyer for material to be treated adapted to be operated by said driven element, a manually operative member adapted to cause engagement and disengagement of said elements, an abutment, means controlled by said abutment adapted to effect disengagement of said elements comprising a pivoted motor-device adapted to engage said manually operative member and move it in a direction to effect disengagement of said elements, a rotatable stop dog movable into and out of the path of said device, a trip arm rotatable with said dog, a trip movable into and out of engagement with said trip arm, and a pivoted arm by which said trip is carried.

22. In an apparatus of the character described, in combination, a driving element, a driven element, a conveyer for material to be treated adapted to be operated by said driven element, a manually operative member adapted to cause engagement and disengagement of said elements, an abutment, means controlled by said abutment adapted to effect disengagement of said elements comprising a pivoted motor-device adapted to engage said manually operative member and move it in a direction to effect disengagement of said elements, a rotatable stop dog movable into and out of the path of said device, a trip arm rotatable with said dog, a trip movable into and out of engagement with said trip arm, a pivoted arm by which said trip is carried, and a rod operatively connected to said last mentioned arm.

23. In an apparatus of the character described, in combination, a driving element, a driven element, a conveyer for material to be treated adapted to be operated by said driven element, a manually operative member adapted to cause engagement and disengagement of said elements, an abutment, means controlled by said abutment adapted to effect disengagement of said elements comprising a pivoted motor-device adapted to engage said manually operative member and move it in a direction to effect disengagement of said elements, a rotatable stop dog movable into and out of the path of said device, a trip arm rotatable with said dog, a trip movable into and out of engagement with said trip arm, a pivoted arm by which said trip is carried, and a rod operatively connected to said last mentioned arm and to said abutment.

24. In an apparatus of the character described, in combination, a driving element, a driven element, a conveyer for material to

be treated adapted to be operated by said driven element, a manually operative member adapted to cause engagement and disengagement of said elements, an abutment, means controlled by said abutment adapted to effect disengagement of said elements comprising a pivoted motor-device adapted to engage said manually operative member and move it in a direction to effect disengagement of said elements, a rotatable stop dog movable into and out of the path of said device, a shaft rotatable with said dog, a trip arm rotatable with said shaft, a manually rotatable sleeve on said shaft, and a trip arm rotatable with said sleeve.

25. In an apparatus of the character described, in combination, a driving element, a driven element, a conveyer for material to be treated adapted to be operated by said driven element, a manually operative member adapted to cause engagement and disengagement of said elements, an abutment, means controlled by said abutment adapted to effect disengagement of said elements comprising a pivoted motor-device adapted to engage said manually operative member and move it in a direction to effect disengagement of said elements, a rotatable stop dog movable into and out of the path of said device, a shaft rotatable with said dog, a trip arm rotatable with said shaft, a manually rotatable sleeve on said shaft, a trip arm setter rotatable with said sleeve, a pivoted arm, and a trip pivotally mounted on said arm.

26. In an apparatus of the character described, in combination, a driving element, a driven element, a conveyer for material to be treated adapted to be operated by said driven element, a manually operative member adapted to cause engagement and disengagement of said elements, an abutment, means controlled by said abutment adapted to effect disengagement of said elements comprising a pivoted motor-device adapted to engage said manually operative member and move it in a direction to effect disengagement of said elements, a rotatable stop dog movable into and out of the path of said device, gear teeth on said dog, a rotatable shaft having gear teeth adapted to mesh with the teeth of said dog, a trip-arm rotatable with said shaft, a manually rotatable sleeve on said shaft, and an arm on said sleeve disposed opposite said trip-arm.

27. In an apparatus of the character described, in combination, a driving element, a driven element, a conveyer for material to be treated adapted to be operated by said driven element, a manually operative lever connected to cause engagement and disengagement of said elements, an abutment, means controlled by said abutment adapted to effect disengagement of said elements comprising a pivoted motor-device disposed

to engage said manually operative lever and move it in a direction to effect disengagement of said elements, and movable means carried by said manually operative lever 5 adapted to engage said motor-device to lock said manually operative lever in predetermined position.

28. In an apparatus of the character described, in combination, a driving element, 10 a driven element, a conveyer for material to be treated adapted to be operated by said driven element, a manually operative member adapted to effect engagement and disengagement of said elements, a motor-device

adapted to operate said member to effect 15 said disengagement, an abutment adapted to be moved under the influence of said conveyer, a dog adapted to hold said motor-device at rest, and connections from said abutment adapted on said movement of said 20 abutment to release said dog.

In testimony whereof I affix my signature, in the presence of two witnesses.

WILLIAM J. GOING.
